UNITED STATES PATENT OFFICE.

ARTHUR L. RUSSELL, OF HYDE PARK, MASSACHUSETTS, ASSIGNOR TO UNITED SHOE MACHINERY COMPANY, OF PATERSON, NEW JERSEY, A CORPORATION OF NEW JERSEY.

MACHINE FOR USE IN THE MANUFACTURE OF BOOTS AND SHOES.

1,024,599.

Specification of Letters Patent.

Patented Apr. 30, 1912.

Application filed June 8, 1908. Serial No. 437,341.

To all whom it may concern:

Be it known that I, ARTHUR L. RUSSELL, a citizen of the United States, residing at Hyde Park, in the county of Norfolk and 5 Commonwealth of Massachusetts, have invented certain Improvements in Machines for Use in the Manufacture of Boots and Shoes, of which the following description, in connection with the accompanying drawings, 10 is a specification, like reference characters on the drawings indicating like parts in the several figures.

This invention relates to machines for use in the manufacture of boots and shoes and 15 more particularly welted shoes, and it has for its object to provide means for removing surplus material at and adjacent to the rear ends of the welt and inseam.

An important feature of the invention 20 consists in welt butting means constructed and arranged to be actuated transversely of the shoe for cutting the welt edgewise.

A further feature of the invention consists in means for holding the welt while it 25 is being cut. Preferably the holding means will comprise one or more clamping members for restraining the welt from displacement during the cutting operation. The holding means herein shown includes a 30 member for yieldingly clamping the welt in the direction of the thickness of the welt while the knife is actuated in the direction of the width of the welt. The illustrated machine is also provided with means for 35 engaging shoe stock at the inner edge of the welt while the cutter advances from the outer edge of the welt.

It frequently happens that the welt attaching stitches of the inseam extend back 40 of the point at which the welt is cut off or beveled and it is necessary to sever the stitches which connect the butt end before the surplus stock can be removed from the shoe.

45 A further feature of the invention consists in a novel construction and arrangement of means for cutting the stitches and severing from the shoe bottom surplus stock to present a suitably even seat for the heel 50 end of the outer sole.

The welt beveling cutter and the stitch

cutter can be, and as herein shown are, formed as a single knife having an angular cutting edge. Coöperating with the cutters is a guard which shields the upper from 55 injury by the cutters during their operation and protects the knife from engagement by the shoe while the latter is being positioned. Preferably the guard is movable from a retracted position in which the 60 placing of the shoe is conveniently effected into a position in the welt crease between the knife and the upper on the side edge of the shoe. The guard plate determines the relation of the cutters to the bottom of the 65 shoe. The knife may conveniently be arranged to have sliding contact with the upper face of the guard. Preferably the guard will be advanced manually from its retracted position to engagement with the 70 shoe so that it can be correctly positioned in the welt crease without liability of injuring the shoe. The cutters will preferably be actuated by power driven mechanism. As herein shown a single manually 75 controlled device with which the guards on the two sides of the machine are yieldingly connected is also operatively connected with the power mechanism for starting the latter by a continued movement. The guard 80 and the cutters are therefore caused to operate successively through the instrumentality of a single manually controlled means, the cutters being advanced and then retracted automatically by the power driven 85 mechanism when the latter is rendered operative. The guard is arranged for movement vertically to find automatically the level of the welt crease of the shoe which is in the machine, and the knife rests upon the 90 guard so that the cutters are automatically positioned vertically for the height of each shoe. The guard also serves as a presser for pushing the shoe stock inwardly to tighten the upper over the edge of the last and position the welt transversely of the shoe bottom. It is frequently found that the end portion of the welt is bent outwardly and the guard and presser force it into normal 95 relation to the shoe bottom and to the path 100 of the cutter and hold it while it is being beveled.

Another feature of the invention consists in means for clearing from the shoe the surplus stock, including the severed butt end of the welt and any other material that may be cut off by the knife.

As herein shown the device hereinbefore referred to as engaging the stock at the inner side of the welt to hold it during the cutting operation is arranged for movement outwardly to clear or drag away from the shoe bottom the surplus stock which has been cut off. This leaves the shoe free and clear to receive the outersole.

The invention is shown as applied to a machine for tightening over a last the shoe stock at and adjacent to the rear ends of the welt, positioning the upper, counter and welt ends correctly and holding these parts of the shoe while the welt butts are cut off and the parts fastened by tacks and compressed to level the heel portion of the shoe bottom preparatory to the sole laying operation.

Certain features of the invention are to be found in the combinations, which will be described, of the positioning, holding, securing and leveling means with the welt butting and stitch cutting means.

Other features of the invention, including certain details of construction and combinations of parts, will be explained in connection with the following description of a preferred construction embodying the invention and will then be particularly pointed out in the claims.

Figure 1 of the drawings is a side elevation of the machine; Fig. 2 is a perspective view showing many of the operating parts; Fig. 3 is a transverse section showing parts particularly concerned with this invention; Fig. 4 is a perspective view of the stitch cutting and welt butting and removing devices; Fig. 5 is a plan view of the knife; Fig. 6 is a perspective view of the rear portion of a shoe, showing the work of the machine.

The column 2 of the machine has support for a treadle 4 connected by means of a rod 5 and intermediate devices with rack bars 6. These rack bars actuate a series of like devices at each side of the shoe. The bars engage pinions 8 arranged to turn shafts 10, each provided with a screw-threaded portion 12 which receives a sleeve 14 loosely mounted on the inwardly projecting arm of a bell crank 15. The bell crank is arranged to turn about an axis 16 fixed in the head of the column and its forward end is pivotally connected to a sleeve 18 adapted to slide on a rod 20. The rod is connected at its inner end to a heel embracing band 26 arranged to extend around the heel portion of the shoe. The band is provided at 35 with a shoe engaging pad which with the band constitutes the back stop for the shoe which is

to be operated upon in the machine. The band is provided near its front ends with extended pads 36 for engaging the sides of the shoe at and adjacent to the front ends of the heel stiffener.

70

The shaft 10 has toothed engagement at its forward end with rack teeth on the sliding carrier 40 which is movable transversely of the machine in suitable guideways formed in the head of the column. The carrier 40 has tongue and groove connection with a block 42 that is arranged for adjustment inwardly and outwardly, and pivotally supports an endwise acting presser 44 which is slotted to embrace a stud 45 which acts through the spring 46 for yieldingly actuating the presser. This presser is provided at its inner end with a thin plate or blade 50 which may be formed to engage the shoe stock with a wiping action at and adjacent to the edge of the last and to enter the crease between the upper and the outwardly projecting sole-attaching flange or welt of the shoe. The presser 44 is arranged for pivotal movement about the stud 45 and is supported from below by an adjustable stop 52, while the blade 50 may also rest upon and be guided by the upper edge of the pad 36 toward position to engage the shoe under the welt. The blade is supported in inclined position so that it will readily slide up the side of the shoe and find the welt crease without any attention from the operator. The carrier 40 also supports on its lower inner edge a wiper 60 beveled at its front end and preferably corrugated on its lower face and adapted to move inwardly over the welt and the inseam to assist the presser blades 50 in tightening the shoe stock over the edge of the last.

105

A spindle 65 supports the shoe against an abutment 66 depending from the machine in position to engage the heel portion of the shoe. This abutment may be arranged to yield upwardly against the tension of a moderately stiff spring 68. The spindle is shown as pivoted at 70 to a rack bar 72 and adapted to swing outwardly into the dotted-line position shown in Fig. 1 to facilitate the application and removal of the shoe. The rack bar 72 extends through a member 74 guided in the side of the column 2 and is engaged by a toothed lever 75 pivoted to the member 74 by which the spindle and the shoe may be manually uplifted to present the shoe in position to be operated upon after it has been swung from the dotted-line position into the full-line position shown in Fig. 1. The lever 75 has a pawl for engaging a ratchet 76 to hold the lever in adjusted position. The member 74 has connection through the link 78 with the upwardly projecting arm of a bell crank lever 80, said arm and link forming a toggle.

The bell crank 80 is pivoted to a bracket 130

extending from the column of the machine and at its rear end is connected by a rod 82 with a crank 84 on a shaft 85, which is mounted in suitable bearings in the head of 5 the column and is driven through gears 86 and 88 from the driving shaft 90, on which runs loosely a pulley 92. A clutch bolt 94 extends from a collar 95 fast on the driving shaft through the gear 88 and into the hub 10 of the otherwise loose pulley 92. The clutch bolt has a pin 96 extending through a slot in the collar 95 into position to be engaged by the inclined face of a clutch controlling device 98. This controlling device is pivotally 15 mounted on a stud 99, which also supports a lever 100 that carries a tilting bar 102, having on its inner end a shoulder 104 adapted to be held by the spring 103 in engagement with the device 98 and withdraw 20 that device from the stud 96 when the lever 100 is rocked. The collar 95 has a stud 106 arranged to engage the inner end of the tilting bar 102 after the machine is started and swing the shoulder 104 downwardly 25 away from the controlling device 98 to permit the spring 108 to return said device into position to engage the stud 96 when the driving shaft has completed one revolution. Any other usual form of one revolution 30 clutch mechanism may be substituted for that described.

The lever 100 above referred to as the actuator for the clutch controlling device is connected by a rod 110 to a block 112 ar- 35 ranged for sliding movement in a frame 114, which constitutes one member of the connection between the treadle rod 5 and the rack bars 6 earlier referred to. This frame 114 has the slide bar 115 arranged for end- 40 wise adjustment by a screw and slot at 116 and formed at its upper end for engagement with the tails of pawls 118 carried by the block 112. This plate 115 holds the pawls out of engagement with a series of 45 ratchet teeth formed on the frame 114 until the frame has been moved downwardly with relation to the block 112 and to said pawls far enough to release the latter. A spring 120 thereupon throws the pawls into en- 50 gagement with the ratchet teeth and the frame and the pawls then form a connection between the treadle rod and the clutch rod 110 by which the latter and the clutch are actuated from the treadle. A spring 122 is 55 arranged to sustain the weight of the block 112 and raise it after it has been depressed by the engagement of the pawls with the frame 114. The upper end of the frame 114 is formed with laterally projecting arms 60 yieldingly connected with the rack bars 6 by the rods 125 and springs 126, one only of which is shown in Fig. 2.

The actuation of the driving shaft when the clutch is operated turns the shaft 85 65 and the crank 84 thereon to communicate

motion to the last supporting spindle for raising the shoe against the wipers 60, whereby the shoe stock engaged by said pressers is compressed and leveled down upon the shoe bottom to form a seat for 70 the outersole. The spring 68 permits the abutment or bottom rest 66 to yield during the compressing operation so that the entire compressing force is received by the wipers 60. The shaft 85 carries also a cam 140 for 75 actuating a rod 142 that extends to a tack separating and delivering mechanism supported on the head of the column. This mechanism may be of any suitable construction adapted to supply a plurality of tacks 80 to the conductors 144 at each operation of the machine. The tack supplying mechanism is timed to deliver the tacks from the conductors into the driver passages when the carrier 40 occupies its retracted position 85 away from the shoe. The driver passages terminate in suitable tack holders mounted in a block 152 detachably secured to the carrier. The drivers 150 are carried by a bar 155 which is guided in the carrier 40 90 and provided on its upper end with a roll for making contact with the driving head 156. This driving head is connected by a link 158 with a crank 160 on the shaft 90. This crank is set to actuate the drivers for 95 inserting tacks into shoe stock while the stock is under compression between the last bottom and the wipers 60. The wipers 60 are recessed to permit tacks to be driven through them and may be connected to the 100 carriers 40 as indicated at 63 in Fig. 2 to permit them to rock laterally for adjusting themselves to the surface of the work.

The pressers 44 are each connected with a bell crank 176 that is pivotally connected at 105 174 with the block 40 and has a lower arm that engages an extension 177 on the carrier 44. The upper arm of the bell crank is connected to a rod 172 which extends upwardly and is guided in the nailing head 110 156. The collar 178 is adjustable on the rod and is positioned to be engaged by the nailing head for slightly retracting the presser blades 50 from the welt crease as the shoe is raised to compress the stock against the 115 wipers, so that the blades will not prevent the crease being closed tightly by the compressing operation. The parts are relatively timed so that the blades hold the shoe stock in its tightened condition until sufficient 120 pressure has been applied so that it is held by the wipers and it is necessary to withdraw the blades only slightly to avoid obstruction to the compression of the stock of the inseam.

The carrier 40 is grooved in its rear side as shown in Figs. 3 and 4 to receive a knife block 1 adjustably connected by a pin and slot at 3 to a lever 7 which is fulcrumed on the carrier at 9 and is connected by a link 130

11 to a block 13 that is attached to and moves with the driver bar 155 to reciprocate automatically the knife block in time relation with the driver. The knife 17 is formed as 5 shown in Figs. 4 and 5 to present a horizontal stitch cutting blade and an inclined welt butting or beveling blade. The knife rests at its inner end upon the upper face of the presser plate 50, which engages the stitches 10 in the inseam crease, to be supported and guided by that plate which constitutes a guard to prevent the knife from injuring the upper. The vertical position of the plate varies, as has been explained, and the knife 15 is therefore arranged to spring up with the blade, being secured to its block by the single screw 19 and the stud 21 and having a relatively narrow shank. While the stitch cutting blade and the welt butting blade might 20 be formed separately, their formation in a single knife both insures a continuous cutting edge for completely severing the surplus portion of the welt from the shoe and also gives to the knife sufficient transverse 25 rigidity to insure the maintenance of its form. The blades are each formed, as shown best in the plan view, to present a slanting edge, the stitch cutting blade severing the stitches progressively and the welt beveling 30 blade engaging first the upper portion of the welt and by its form tending to hold the welt down as the cutting progresses. To assist in holding the welt the wiper 60 has a companion block 61 that is yieldingly connected 35 to the wiper 60 to subject the surplus end portion of the welt to a yielding holding pressure during the welt butting operation and thereby insure a clean cut and an even bevel. The welt which is damp or in temper 40 at the time it is sewed to the shoe is yet in condition to cut easily at the time the shoe reaches the welt butting and, of course, it cuts easier by passing the knife edgewise through the welt than if the knife cut down 45 upon the welt as has been heretofore proposed. The knife not only bevels the welt and severs any stitches that may extend back of the welt butting point but also preferably advances inwardly beyond the inseam to 50 plane off any upstanding portion of the upper or innersole lips that may project into its path whereby an even seat for the heel portion of the outersole is produced. For removing the surplus stock after it is severed 55 the clearer 23 is yieldingly carried by the wiper 60 to slide inwardly over the welt and then drop down behind it into position to pull out the surplus stock that has been cut off as the wipers are retracted after the 60 pressing, cutting and tacking operations. The clearer 23, while occupying its innermost position, serves the additional purpose of means to engage the welt or the inner side of the between-substance adjacent to the 65 welt, and resist inward displacement of the

welt by the cutter 17. The clamp 61 may be fastened directly to the clearer 23.

In the use of the machine a shoe, which may have been previously lasted and welted, may be applied to the spindle 65 as indicated in dotted lines in Fig. 1. The shoe is swung into the full-line position, during which movement it is thrust into the heel embracing band and stopped against the pad 35. The pad together with the band will have 75 been positioned by suitable adjusting devices so that the shoe will be stopped with the end portions of the welt and the other portions of the shoe in suitable relation to the knives 17 and the other operating devices. When the shoe has been properly positioned the treadle 4 is depressed and through the rack bars 6 rotates the shafts 10. These shafts through the devices connected with them first move the pads 36 80 against the sides of the shoe, firmly clamping the shoe stock against the sides of the last. The presser blades 50 are also actuated inwardly to engage the shoe stock in the welt crease, exerting their inward pressure 90 against the upper and the welt and finally against the inseam to force the welt and the inseam inwardly toward the middle of the last, tightening the upper and stiffener over the edge of the last and holding it under 95 tension. The two wipers 60 move inwardly with the presser blades and by the engagement of their roughened surface with the upper face of the welt assist in tightening the shoe stock over the edge of the last and holding it, particularly the welt, in proper 100 relation to the last bottom and against displacement during the cutting and other operations, the clamps 61 resting yieldingly on the welt with just sufficient pressure to hold 105 it against displacement by the cutting knives.

If desired, the treadle may be moved up and down to press the stock into place and position the welt accurately by repeated movements of the described devices engaging the shoe. To enable such repeated movement of the treadle to be effected without liability of actuating the clutch a sliding stop 199 may be arranged, as shown in Figs. 110 1 and 2, to stand normally under the carrier 114 and prevent the treadle being depressed far enough to disturb the clutch. This stop device is arranged to be readily withdrawn against the tension of its spring 198 when the stock has been forced into position to be 115 compressed and secured. A final or further depression of the treadle serves to move downwardly the carrier 114 and when the plate 115 slides off the tails of the pawls 118 the pawls engage the ratchet teeth on the 120 carrier and through the described connections cause the clutch controlling device 98 to be withdrawn from the path of the pin 96, whereupon the clutch bolt is automatically 125 thrown into engagement with the con- 130

tinuously rotating pulley 92 and the shafts 90 and 85 are caused to make one complete revolution and are then arrested by the clutch controlling device. In this rotation 5 of the shafts the crank 84 effects the elevation of the heel spindle, thus forcing the shoe upwardly against the wipers 60 and compressing the stock covered by the wipers against the bottom face of the last. While 10 the stock is held under compression the crank 160 effects the depression of the driver bars and thereby the actuation of the knives 17 for butting the welt, cutting the inseam stitches back of the bottom point and planing off any projecting portions of the stock 15 so that an even heel seat will be made. The driving of the tacks will be effected while the cutters are operating, the tacks being inserted by pressure rather than by impact. 20 It will be noted that the wipers 60 act at and adjacent to the location of the heel breast. By compressing this stock a firm seat is made for the heel breast. The yielding connections 125, 126 between the treadle and 25 the rack bars 6 permit the final depression of the treadle for operating the clutch. As the parts are retracted to their starting positions the clearers 23 dislodge from the shoe the surplus stock that has been cut off by 30 the knives. The blades 50 extend between the cutting edges of the knives and the shoe upper at all times except when the knives are advanced to do their work and at that time the blades form guards and guides that 35 prevent injury of the upper by the knives on the side of the shoe and in the crease as will be seen from the drawings.

Having explained the nature of this invention and described a construction embodying the same in a preferred form, I 40 claim as new and desire to secure by Letters Patent of the United States:

1. A machine of the class described, having in combination welt butting knives arranged to operate simultaneously at opposite sides of a shoe, means to position the shoe relatively to said knives to cause their operation to take place at predetermined points on the shoe, and means for actuating 45 said knives transversely of the shoe to butt the welt ends widthwise.

2. A machine of the class described, having in combination means for holding the end portion of the welt of a lasted and welted shoe 55 in a plane substantially parallel to the plane of the shoe bottom, a welt butting knife arranged for movement widthwise of the welt and in a plane at an oblique angle to the face of the welt, and means for actuating said 60 knife to sever the end portion of the welt from the body thereof.

3. A machine of the class described, having in combination a welt butting knife arranged for cutting movement widthwise of 65 the welt, means to position the shoe rela-

tively to said knives to cause their operation to take place at predetermined points on the shoe, a guard arranged between the welt and the upper in the inseam in position to protect the upper from being injured by the welt butting knife, and means for actuating the knife. 70

4. A machine of the class described, having in combination a welt butting knife arranged for movement widthwise of the welt; welt holding means including a plate to extend between the welt and the upper in the inseam in position to protect the upper from being injured by the welt butting knife, and an opposed relatively yielding clamping member; and means for actuating the knife over the plate and transversely of the shoe 75 to butt the welt. 80

5. A machine of the class described, having in combination a welt butting knife, means for actuating the knife transversely of the shoe to cut the welt by a stroke from the outer edge of the welt toward the inseam, and a guard plate movable transversely of the shoe into an operative position in the welt crease. 85

6. A machine of the class described, having in combination welt butting knives, guard plates adapted to enter the welt crease at opposite sides of the shoe, means 90 for moving the guard plates transversely of the shoe toward and from operative position, and means for actuating the knives over the guard plates in a direction transverse of the shoe to effect cutting of the welt 95 widthwise. 100

7. A machine of the class described, having in combination welt butting knives, guard plates adapted to enter the welt crease at opposite sides of the shoe, and means for actuating the guard plates and the knives having provision for moving the plates into operative position before the knives are advanced and then advancing the knives transversely of the shoe to effect 110 cutting of the welt widthwise. 105

8. A machine of the class described, having in combination a welt butting knife, a guard arranged to extend between the welt and the shoe upper, and connected mechanism for actuating the guard manually to cause a power driven operation of the knife to be effected. 115

9. A machine of the class described, having in combination a welt butting knife, a guard arranged to extend between the welt and the shoe upper, means for manually actuating the guard into operative position, and connected power-driven means for actuating the knife to butt the welt. 120

10. A machine of the class described, having in combination a welt butting knife, a guard arranged to extend between the welt and the shoe upper, and connected mechanism for actuating the guard and the knife 125 130

transversely of the shoe, said mechanism having provision for permitting the movement of the guard to be arrested by its engagement with the inseam and for causing the knife to cut the welt after the guard comes to rest.

11. A machine of the class described, having in combination a welt butting knife, a guard arranged to extend between the welt and the shoe upper, and connected mechanism for positioning the guard and, at the will of the operator, thereafter actuating the knife.

12. A machine of the class described, having in combination a guard arranged to extend between the welt and the upper in the welt crease, a welt butting knife arranged to rest on the guard, and means for actuating the knife over the guard transversely 20 of the shoe to butt the welt.

13. A machine of the class described, having in combination a device arranged to engage the shoe in the inseam adjacent to the end of the welt, means for actuating said device to position the end portion of the welt transversely of the shoe and hold it pressed in, and a welt butting knife arranged to cut across the welt transversely for beveling the welt.

14. A machine of the class described, having in combination means for butting the welt of a lasted and welted shoe, and means for positively engaging the severed portion of the welt and having an automatic movement to force it from the shoe.

15. A machine of the class described, having in combination means for abutting a welt, and clearers movable transversely of the shoe to remove the severed portions of the stock.

16. A machine of the class described, having in combination means for butting a welt, clearers movable transversely over the welt and downwardly behind the portion to be cut off, and means for actuating the clearers to remove the cut-off portion of the welt.

17. A welt butting machine, having in combination means for clamping the end portion of the welt of a lasted and welted shoe, and means movable relatively to the clamping means, for severing a portion of the welt held by the clamping means from the body of the welt which remains attached to the shoe.

18. A welt butting machine, having in combination automatically operating means for clamping the end portion of the welt, and means moving perpendicularly to the direction of the clamping pressure and relatively to the clamping means to butt the welt.

19. A welt butting machine, having in combination means to position a lasted shoe 60 having an attached welt, a welt butting knife

having a cutting edge extending oblique to the plane of the shoe bottom, and means for actuating the knife to butt the welt.

20. A welt butting machine, having in combination welt clamping means, mechanism for manually actuating said clamping means to embrace the welt, automatically operating mechanism for relatively actuating said means to clamp the welt, and means for removing surplus stock at the end 70 of the welt.

21. A welt butting machine, having in combination means for clamping the welt in the direction of its thickness, and means for cutting the welt in the direction of its width from edge to edge to butt the welt while it remains clamped.

22. A welt butting machine, having in combination means for holding the welt in the direction of its thickness, means for cutting the welt in the direction of its width from edge to edge to butt the welt while it remains clamped, and automatically operating mechanism for actuating the clamping and the cutting means.

23. A welt butting machine, having in combination means for positioning a lasted and welted shoe, devices for beveling the two ends of the welt simultaneously and devices that are automatically engaged over the surplus stock in the rear of the beveled ends and are actuated to force it from the shoe outwardly toward opposite sides of the shoe, and mechanism for operating said devices.

24. A welt butting machine, having in combination means for beveling the end of the welt of a shoe, means for compressing the end portion of the welt against the shoe bottom, and means for evening the shoe bottom in the rear of the bevel.

25. A welt butting machine, having in combination means for beveling the end of the welt of a shoe, means for compressing the end portion of the welt against the shoe bottom, and means for removing surplus stock in the rear of the bevel.

26. A welt butting machine, having in combination means for beveling the end of the welt of a shoe, means for compressing the end portion of the welt against the shoe bottom, and means for cutting surplus stock from the shoe bottom in the rear of the bevel, and devices for clearing the surplus stock from the shoe after it is cut.

27. A machine of the class described, having in combination a trimming knife relatively to which a shoe is to be moved into position to be operated upon, means for actuating the knife, a guard normally occupying a position to protect the knife from engagement by the shoe and movable into position to shield the shoe upper from injury by the knife when the latter is actuated.

28. A machine of the class described, having in combination a knife 17 having cut-

ting edges arranged to bevel a welt and cut stitches which may connect the butt end of the welt to the shoe, and means for reciprocating the knife transversely of the shoe to do its work, substantially as described.

29. A machine of the class described, having in combination a knife constructed and arranged to bevel a welt and cut stitches which may connect the butt end of the welt to the shoe, and means for engaging the shoe in the welt crease to position the knife with relation to the welt.

30. A machine of the class described, having in combination a knife constructed and arranged to bevel a welt and cut stitches which may connect the butt end of the welt to the shoe, said knife having its stitch cutting edge and its welt cutting edge reversely inclined, and means for actuating the knife.

31. A machine of the class described, having in combination a knife constructed and arranged to bevel a welt and cut stitches which may connect the butt end of the welt to the shoe, said knife having a cutting edge inclined to the lines of stitches, and means for actuating the knife transversely of the shoe bottom.

32. A machine of the class described, having in combination a welt butting knife, means for actuating the knife transversely of the shoe bottom to cut the welt edge-wise, means for engaging the shoe stock at the inner edge of the welt to hold it during the cutting operation and means for actuating the engaging means to dislodge from the shoe the portion of the welt cut off by the butting knife.

33. A machine of the class described, having in combination a positioning device arranged to engage a welted shoe in the welt crease and to yield vertically to find the level of the crease automatically, means for actuating the positioning device transversely of the shoe, a knife for removing surplus stock from the bottom of the shoe, said knife being arranged to rest upon said positioning device for movement vertically therewith relatively to the shoe bottom, and means for actuating the knife transversely of the shoe in sliding contact with said device to do its work.

34. A machine of the class described having, in combination, means for butting the two ends of the welt of a welted and lasted shoe, power actuating mechanism therefor and a treadle and connections arranged for manipulation for relatively positioning the shoe and the cutters and for further movement to start said power actuating mechanism for the cutters.

35. A machine of the class described, having in combination a knife for trimming the shoe stock on the bottom of a shoe, means for reciprocating the knife transversely of the shoe bottom to do its work, a

guard arranged to extend into the welt crease to protect the upper from the action of the reciprocating knife and means for reciprocating the guard.

36. A machine of the class described, having in combination a knife for butting a welt, means for actuating the knife transversely of the shoe bottom, and a guard normally extending beyond the cutting edge of the knife and adapted to enter the welt crease to protect the upper from injury by the knife.

37. A machine of the class described, having in combination a knife for butting a welt, means for actuating the knife transversely of the shoe bottom, to butt the welt, and a guard arranged to enter the welt crease in advance of the knife for protecting the upper from injury by the knife and over which the knife moves in doing its work.

38. A machine of the class described, having in combination a knife for cutting the inseam stitches at the butt end of a welt, means for actuating the knife transversely of the shoe bottom, and a guard normally projecting in advance of the cutting edge of the knife and adapted to precede the knife into engagement with the shoe in the welt crease.

39. A machine of the class described, having in combination a guard adapted to enter the welt crease, said guard being movably mounted to permit it to adapt its position automatically to that of the shoe, and a knife arranged to take its position from that of the guard and means to actuate the knife transversely of the shoe to butt the welt and cut stitches connecting the severed portion of the welt to the shoe.

40. A machine of the class described, having in combination a guard, means to actuate the guard to find operative relation to the shoe, a knife arranged to take its operative relation to the shoe from the position of the guard, and means for projecting the knife beyond the guard to cut the stock and for retracting the knife into position to have its cutting edge protected by the guard.

41. A machine of the class described, having in combination a guard to enter the welt crease, manually controlled means for positioning the guard, a knife movable transversely of the shoe bottom to trim the shoe stock thereon, and automatically operating means for actuating the knife.

42. A machine of the class described, having in combination a knife for removing surplus stock from the bottom of a welted shoe, a knife positioning device by which the knife may be moved and which is arranged to slide up the side of the shoe until it enters the welt crease, said knife being yieldingly mounted to have its cutting edge sprung upwardly by the movement of said device into position to trim the surplus stock from the

shoe close to the plane of the upper that is on the margin of the shoe bottom.

43. A machine of the class described having, in combination, a welt butting knife, a support for engaging under the shoe to hold it up in position to be operated upon, means for positioning the knife relatively to the welt of the shoe that is on said support, and power driven means for actuating the knife 10 to cut the welt.

44. A machine of the class described, having, in combination, means for positioning the butt end portion of the welt of a lasted and welted shoe, means for butting the welt, 15 means for inserting a tack relatively to the welt while the welt is held by said positioning means, and a support engaging under the shoe to sustain it for the tack inserting operation.

45. A machine of the class described, having, in combination, means for positioning the butt end portion of the welt of a lasted and welted shoe, means for butting the welt, means for inserting a tack relatively to the 20 welt while the welt is retained in the position to which it was moved by said positioning means, and a shoe support with relation to which said means are arranged to operate without substantial change in the position of 25 the shoe during the operation of said means, said support being arranged to engage under the shoe for upholding the shoe against the action of the tack inserting means.

46. A machine of the class described, having, in combination, means for butting simultaneously the two ends of the welt of a lasted and welted shoe, means for tacking the welt ends, means for positioning the welt 30 ends for the butting and tacking operations, and additional means for engaging under the shoe to uphold the shoe for the tacking operation.

47. A machine of the class described, having, in combination, a shoe support, means for positioning the butt end portion of a welt of a lasted and welted shoe, means for butting the welt, and means for inserting a tack relatively to the welt while the welt is held by said positioning means, said support 40 including the spindle 65 to engage under the shoe and uphold it against depression by the tack inserting means.

48. A machine of the class described, having, in combination, means for positioning the butt end portion of the welt of a lasted shoe, means for butting the welt, means for compressing the shoe stock including the 45 previously positioned welt against the last bottom at and adjacent to the welt end, and means for inserting a tack.

49. A machine of the class described having, in combination, means at opposite sides of the shoe engaging in the welt crease to tighten the upper about the last and position 50 the butt ends of the welt on the insole, welt

butting cutters arranged and actuated to cut the welt ends by a movement transversely of the machine and widthwise of the welt, and yielding welt pressers mounted in advance of said cutters to engage the upper surface 70 of the welt.

50. A machine of the class described having, in combination, cutters for butting the two ends of a welt, means for actuating said cutters transversely of the shoe to cut through the welt from its outer edge toward the inseam, and cutter plates co-operating therewith extending in the welt crease at each side of the shoe at and adjacent to the end of the inseam and also inward over the insole and beneath the unsecured ends of the welt.

51. A machine of the class described having, in combination, a pair of heads one at each side of the machine, means to move said heads apart to permit positioning of the heel end of a welted shoe therebetween, a welt butting cutter carried by each of said heads, and means to move said heads inward after a shoe has been positioned to bring said cutters into cutting relation with the welt ends and means for actuating the cutters transversely of the shoe for cutting through the welt ends widthwise.

52. A machine of the class described having, in combination, cutters for butting the two ends of the welt of a welted shoe by a movement widthwise of the welt inwardly over the shoe bottom, means for actuating the cutters simultaneously over the shoe, and guards extending between the welt and the upper in the welt crease to protect the upper from the action of the cutters.

53. A machine of the class described having, in combination, cutters for butting the two ends of the welt of a welted shoe by a movement widthwise of the welt inwardly over the shoe bottom, means for actuating the cutters simultaneously over the shoe, and guards movable laterally of the shoe to embrace it in the welt crease at opposite sides and determine the position of the welt with relation to the path of the cutters to cause the welt ends to be severed on a bevel while protecting the upper from the cutters.

54. A machine of the class described having, in combination, means for positioning a shoe and welt butting means movable simultaneously from opposite sides of the shoe toward its median portion in a plane relative to the shoe positioning means to cut the two welt ends from the outer edge inwardly on a bevel.

55. A machine of the class described having, in combination, means for positioning a shoe, welt butting means movable simultaneously from opposite sides of the shoe toward its median portion in a plane relative to the shoe positioning means to cut the two welt ends from the outer edge inwardly on 125 130

a bevel, and means coöperating with each cutter for actively pressing the welt down while it is being cut.

56. A machine of the class described having, in combination, means for positioning a shoe, welt butting means movable simultaneously from opposite sides of the shoe toward its median portion in a plane relative to the shoe positioning means to cut the two 10 welt ends from the outer edge inwardly on a bevel, and a thin edged support for the outer portion of the welt shaped to extend in the welt crease substantially to the bottom thereof to guide the cutter out of contact 15 with the upper that overlies the feather of the shoe innersole.

57. A machine of the class described having, in combination, means for positioning a shoe, welt butting means movable simultaneously from opposite sides of the shoe toward its median portion in a plane relative to the shoe positioning means to cut the two 20 welt ends from the outer edge inwardly on a bevel, and means movable to engage the welt 25 or the inner side of the between-substance adjacent thereto and resist inward displacement of the welt by the action of the cutter.

58. A machine of the class described having, in combination, means for positioning a shoe, welt butting means movable simultaneously from opposite sides of the shoe toward its median portion in a plane relative to the shoe positioning means to cut the two 30 welt ends from the outer edge inwardly on a bevel, means movable to engage the welt or the inner side of the between-substance adjacent thereto and resist inward displacement of the welt by the action of the cutter, and means to actuate the last named means 35 40 outwardly after the butting operation to remove the waste from the shoe.

59. A machine of the class described having, in combination, upper tightening means arranged to operate at and adjacent to the 45 rear ends of the welt of a welted shoe, means for inserting fastenings to secure the upper in tightened condition, means for butting the welt ends, and devices for supporting and positioning a shoe for the operation of 50 said means at the proper points thereon including provision for upholding the shoe substantially rigidly against the impact of the inserting devices.

60. A machine for butting welts, having, 55 in combination, a welt butting cutter, and a welt butt ejector operating to dislodge the severed welt butt by a movement transversely across the shoe.

61. A machine for butting welts, having, 60 in combination, a welt butting cutter mounted on a suitable support, operating means for the cutter, and a welt butt ejector separately mounted on the cutter support.

62. A machine for butting welts, having,

in combination, a welt butting cutter, a 65 presser acting on the welt in advance of the operation of the cutter, and an ejector for dislodging the welt butt after its severance.

63. A machine of the class herein described, having, in combination, means for 70 supporting a lasted and welted shoe, means for positioning a butt end of the welt, means for beveling the welt, and means for tacking down the welt.

64. A machine of the class herein described having, in combination, a shoe support, a knife arranged to cut the welt, a rest to support the welt against the cutting action of the knife, and a tacker to fasten 75 the end of the welt. 80

65. A machine of the class herein described having, in combination, means for supporting a lasted and welted shoe, means for supporting the two butt ends of the 85 welt, means for beveling said two ends simultaneously, and welt butt tacking means.

66. A machine of the class herein described having, in combination, means for butting a welt, means for pressing the welt end inwardly, means for inserting a tack 90 adjacent to the welt end while the pressure is maintained, and means in addition to said welt end pressing means for upholding the shoe against the action of the tack inserting means. 95

67. A machine of the class herein described having, in combination, a shoe support, welt butting means, means to position the welt end transversely of the shoe bottom, and welt end fastening means. 100

68. A machine of the class herein described having, in combination, means for butting the opposite ends of a welt simultaneously, means for engaging the welt crease laterally to press the welt end inwardly, means to fasten the shoe stock while the welt is so pressed inwardly, and additional means for upholding the shoe against the action of the fastening means. 105

69. A machine of the class herein described having, in combination, rests for the two ends of the welt of a welted shoe, a support extending under the shoe to uphold it, coöperating cutters, and a welt end tacker. 110

70. A machine of the class herein described having, in combination, rests for the two ends of the welt of a welted shoe, co-operating cutters for the two welt ends, said rests being arranged to form transversely acting positioning means for the welt, tack 115 driving means, and additional means for upholding the shoe against depression by the operation of the tack driving means. 120

71. A machine of the class herein described having, in combination, means for butting a welt, means for tightening the upper over the last bottom adjacent to the end of the welt, means for tacking the up- 125

- per, and means in addition to the said upper tightening means for upholding the shoe against depression by the tack inserting means.
- 5 72. A machine of the class herein described having, in combination, means for butting a welt, means for tightening the upper over the last bottom in the region of the welt end, a tacker adapted to fasten the 10 upper and the welt end, and means in addition to the upper tightening means and which is arranged to engage the body of the shoe for upholding it for the operation of said other means.
- 15 73. A machine of the class herein described having in combination, a welt butter, a welt butt tacker and a shoe support arranged to present the shoe for the butting and the tacking operations.
- 20 74. A machine of the class herein described having in combination, a welt butter, a welt butt tacker, a shoe support, constructed and arranged to present the shoe for the butting and the tacking operations, 25 and operating mechanism for lifting the support to compress the stock against the tacker prior to the insertion of the tack.
75. A welt butting machine, having welt butting blades for the two ends of the welt 30 movable transversely of the shoe and arranged with their cutting edges at acute angles to the median line of the shoe.
76. A machine of the class described, having in combination, means to butt a 35 welt, means to press inwardly over the shoe bottom the stock adjacent to the end of the welt, means to tack the stock to secure it while it is so pressed, and means to effect compression of the stock substantially perpendicular to the plane of the shoe bottom.
77. A machine of the class described, having in combination, means to butt simultaneously the two ends of the welt of a welted shoe, means to tighten the upper over the 45 last bottom adjacent to a butt end of the welt, means to secure the upper in tightened relation to the last, and means to compress the shoe stock against the last bottom adjacent said end of the welt.
- 50 78. A machine of the class described, having in combination, stitch cutting means, welt butting means, upper tightening means, and tacking means, said machine comprising means constructed and arranged to engage the body of the shoe below the welt 55 for firmly upholding the shoe against the action of the tacking means.
79. A machine of the class described, having in combination, stitch cutting means, 60 welt butting means, welt butt holding down means, upper tightening means, tacking means, and means for upholding the shoe firmly against the action of the tacking means.
80. A machine of the class described, having in combination, stitch cutting means, welt butting means, upper tightening means, stock compressing means, and tacking means. 65
81. A machine of the class described, having, in combination, a cutter to sever the inseam stitches, a blade to tighten the upper, a tacker to fasten the upper and a support extending under the shoe to uphold it against the action of the tacker. 70
82. A machine of the class described, having, in combination, a cutter to sever the inseam stitches, a cutter to butt the welt, a tacker to fasten the welt end, and means engaging under the body of the shoe to uphold it against the action of the tacker. 75
83. A machine of the class described, having, in combination, a cutter to sever the inseam stitches, a cutter to butt the welt, a blade to tighten the upper, a tacker to fasten the upper, and additional means to uphold the shoe for the operation of said devices. 80
84. A welt butting machine, having, in combination, welt locating, stitch cutting, 90 welt butting and welt fastening devices, and means for operating said devices, means extending under the body of the shoe to uphold it for the action of said devices.
85. A welt butting machine, having, in combination, means constructed and arranged to extend under the body of a shoe to support the shoe sole up, a laterally movable welt support adapted to engage the underside of the welt, and an independently 100 mounted, laterally movable welt butting cutter above said welt support and operating thereover to butt the welt on an incline. 95
86. A welt butting machine, having, in combination, a welt locator, a stitch cutter, 105 a welt butting cutter, an actuator for said welt locator, and an actuator for said stitch and welt butting cutters, said parts being constructed and arranged to effect the cutting stroke of said cutters transversely of 110 the welt and inseam.
87. A welt butting machine, having, in combination, a welt butting cutter, a stitch cutter, means for operating said cutters, a welt support mounted independently of 115 both of said cutters, and a separate support for the body of the shoe relatively to which the welt support is movable to adapt its position for shoes of different vertical depth.
88. A machine of the class described, having in combination welt butting knives arranged to operate simultaneously at opposite sides of a shoe, and means for actuating said knives transversely of the shoe to do their work. 120
89. A machine of the class described, having in combination a welt butting knife arranged for movement widthwise of the welt 125

to butt the welt, a guard arranged between the welt and the upper in the inseam in position to protect the upper from being injured by the welt butting knife, and means 5 for actuating the knife.

90. In a welt butting apparatus resting and positioning devices for the two butt end portions of the welt of a shoe, said devices being arranged with welt supporting surfaces 10 oppositely inclined to the vertical longitudinal plane of the apparatus.

91. In a welt butting apparatus resting and positioning devices for the two butt end portions of the welt of a shoe, said devices 15 being formed and arranged with their lower faces which lie adjacent to the shoe oppositely inclined downwardly and outwardly

with relation to the vertical longitudinal plane of the apparatus.

92. A machine of the class described having, in combination, means for butting the two ends of the welt of a welted and lasted shoe, a support for the shoe, and a treadle and connections for effecting first a relative positioning of the shoe and the cutters and 20 then causing the cutters to do their work. 25

In testimony whereof I have signed my name to this specification in the presence of two subscribing witnesses.

ARTHUR L. RUSSELL.
